UNITED STATES PATENT OFFICE.

OBED CHARLES HAWKES, OF BIRMINGHAM, COUNTY OF WARWICK,
ENGLAND.

DESIGN FOR BEVELED GLASS.

SPECIFICATION forming part of Design No. 18,549, dated August 21, 1888.

Application filed July 11, 1888. Serial No. 279,670. Term of patent 14 years.

To all whom it may concern:

Be it known that I, OBED CHARLES HAWKES, a subject of the Queen of Great Britain, residing at Birmingham, in the county of Warwick, England, have invented and produced a new and original Design for Beveled Glass, of which the following is a specification, reference being had to the accompanying drawings, forming part thereof.

10 The leading feature of my design for beveled glass is a doubly-sloping channel within the beveled rim of the glass.

Figure 1 represents a section of a piece of beveled glass embodying my invention. Fig. 15 2 represents a face view thereof.

In the drawings, A represents a piece of

glass having on its face a beveled rim, a, and a doubly-sloping channel, b, within the rim and adjacent thereto, one wall of said channel joining the top of the rim, substantially as shown and described.

I claim—

A design for beveled glass having on its face the beveled rim a, and the doubly-sloping channel b within and adjacent to said rim, one wall of said channel joining the top of the rim, substantially as shown and described.

OBED CHARLES HAWKES.
